(57) **CLAIM**

The ornamental design for a three-port high performance mini hollow fiber membrane contactor, as shown and described.

DESCRIPTION

FIG. 1 is a perspective view of a three-port high performance mini hollow fiber membrane contactor showing our new design;

FIG. 2 is first side elevational view thereof;

FIG. 3 is a second side elevational view thereof;

FIG. 4 is a third side elevational view thereof;

FIG. 5 is a fourth side elevational view thereof;

FIG. 6 is a top plan view thereof; and,

FIG. 7 is a bottom plan view thereof.
